UNITED STATES PATENT OFFICE.

PATRICK BURKE, OF MALONE, NEW YORK.

IMPROVEMENT IN HOG-PENS.

Specification forming part of Letters Patent No. **147,306**, dated February 10, 1874; application filed October 25, 1873.

To all whom it may concern:

Be it known that I, PATRICK BURKE, of Malone, in the county of Franklin and State of New York, have invented a new and useful Improvement in Hog-Pen, of which the following is a specification:

Figure 1 is a vertical longitudinal section of my improved hog-pen taken through the line *x x*, Fig. 2. Fig. 2 is a vertical cross-section of the same taken through the line *y y*, Fig. 1. Fig. 3 is a detail view, showing the arrangement of the hooks for the door-hinges. Fig. 4 is a detail view of the sleeping-compartment of the pen, showing the strips or fenders applied to the wall of the same.

Similar letters of reference indicate corresponding parts.

This invention relates to a hog-pen which is so constructed as to offer protection from cold to the occupants thereof; and it consists chiefly in dividing the pen into two compartments by means of a partition-wall, which is provided with self-closing doors opening in opposite directions, and operated by the pigs, so as to enable the same to pass from one compartment into the other. The invention further consists in applying to the side walls of the compartment employed for sleeping purposes a series of strips or fenders, which are placed at such distances apart from each other as to form spaces for permitting the young pigs to enter the space in the rear of or between the fender-plates, so as to prevent the same from being injured or crushed to death when the sow lies down.

A represents the walls of the pen, which, when boarded upon the outer side, should be filled in with brick, four and a half or five feet high, and the whole of the pen, or the part in which the hogs sleep, should be planked upon the inner side. *B* is a spout about four inches deep, secured between two sleepers, *C*. The floor *D*, when laid, should project over the spout *B* half an inch or more, so as to conduct the wet from the floor into the spout *B* to be carried off. The end or corner where the hogs are to sleep is separated from the rest of the pen by a partition, *E*, in which are

formed two doorways for the doors *F*, which doors should open in opposite directions, or one should open inward and the other outward. The doors *F* are hung upon hooks *G* attached to the posts of the door-frames, and the lower hook *G* should be made about half an inch longer than the upper hook. The door-frames should also have an inclination of about half an inch in the direction in which the door opens.

By this construction the doors may be readily pushed open by the hogs—the one to pass in and the other to pass out—without conflict, and will close themselves as the hog passes through.

If desired, the doors *F* may have cords *H* and weights *I* connected with them to draw them shut; but this is not necessary, as the weight of the doors is sufficient for this purpose.

The compartment in which the hogs sleep should have a second floor, *J*, laid upon scantlings resting upon the floor *D*, and about four inches in diameter, which floor, *J*, should have numerous holes bored through it to allow the wet to flow through to the floor *D*, and thence out through the spout *B*. The doors *F* should have a plank about six inches high below them, to prevent said doors from being obstructed by litter in the pen.

The top floor or cover of the pen should be made air-tight, and should be provided with ventilators to allow the air to be excluded in cold weather and admitted in warm weather.

From the spout *B* the liquid refuse from the pen is conducted beneath the wall and into a cistern, whence it can be conveniently taken for manure. This arrangement prevents the cold from entering the pen through the spout *B*.

In addition to the number of pigs killed by the cold, a great many are killed by the sow crushing them against the wall in lying down. To prevent this, I employ strips of wood or fenders *K*, the lower ends of which are secured to the floor about two feet from the wall, and their upper ends rest against and are secured to the walls. These strips should be far enough apart to allow the pigs to pass

through between them, and thus get out of the way.

Having thus described my invention, I claim as new and desire to secure by Letters Patent—

1. A hog-pen divided into two compartments by a partition-wall, said partition being provided with two self-closing doors opening in opposite directions, so as to permit the hogs to pass from one compartment into the other, substantially as herein shown and described.

2. In a hog-pen, the strips or fenders K ap-

plied at the junction of the wall and floor of the sleeping-compartment, forming spaces or stalls for the escape of the young pigs from injury, substantially as and for the purpose set forth.

PATRICK ^{his} X BURKE.
